(57) **CLAIM**

The ornamental design for a window squeegee for flat and curved windows as shown and described.

DESCRIPTION

FIG. 1 is a perspective view for a window squeegee for flat and curved windows showing my new design;

FIG. 2 is a front elevation view thereof;

FIG. 3 is a top plan view thereof;

FIG. 4 is an elevational view taken from the left side thereof;

FIG. 5 is an elevational view taken from the right side thereof;

FIG. 6 is a back plan view thereof; and,

FIG. 7 is a bottom plan view thereof.

The broken lines are shown for purposes of illustrating parts of the article that form no part of the claimed design.
